UNITED STATES PATENT OFFICE.

HARRIET H. HOGE, OF PORTLAND, OREGON.

VAPOR FACE-BATH.

SPECIFICATION forming part of Letters Patent No. 527,758, dated October 16, 1894.

Application filed August 24, 1893. Renewed September 24, 1894. Serial No. 523,986. (No model.)

To all whom it may concern:

Be it known that I, HARRIET H. HOGE, a citizen of the United States, residing at Portland, Multnomah county, and State of Oregon, have 5 invented a new and useful Improvement in Vapor Face-Baths, of which the following is a specification, reference being had to the accompanying drawings, as a part hereof.

My invention relates to contrivances adapted to be used as a hot vapor bath for the face, or for inhaling hot medicated vapors. To derive any beneficial results from either operation it is desirable that the bath be endured, or the inhalation continued for a considerable length of time; but if the patient is compelled to breathe the hot vapors these soon become so stifling that it is impossible to stand it for any great length of time. I therefore conceived the idea of providing the bath with 10 an air-duct, through which the patient will be supplied with fresh air from the exterior of the bath, which, while in no way interfering with the medicinal benefits to be derived from the bath, would enable the patient to 15 endure the hot vapors for a longer time, and thus obtain greater benefits therefrom. With this object in view I have constructed an apparatus as shown in said accompanying drawings, in which—

30 Figure 1, is a perspective view of my invention, illustrating the manner of using the same; and Fig. 2 is a vertical section.

The reference letters designate the parts referred to.

35 My apparatus may be made of sheet metal, and I prefer to construct the same in two sections A, A', the latter being a receptacle for the hot water, and the former being intended to receive the head.

40 When using the bath the two flaps, b, project over the patient's shoulders on each side of the face and help to support a covering

thrown over the patient's head so as to inclose the vapors, the front edge of the covering resting on the shield, d, care being taken 45 to leave the funnel or mouth, e, of the tube or air-duct, f, uncovered. The said air-duct f leads from the exterior to the interior of my apparatus, and the same may consist of a funnel e, secured in the front wall of the upper 50 section A, a rubber, or other flexible tube f, attached to the inside end of such funnel, and a mouth-piece f', provided for the convenience of the patient, he holding the same in his mouth when using my apparatus as a face 55 bath. The mouth of the funnel may also be provided with some means as a piece of silk, linen, or sieve of fine mesh, to filter the air entering through said air-duct.

Both of the sections, A, A', are adapted to 60 be put together, the rim of the lower section, A', being large enough to receive the upper section, A, and having an annular projecting rib, c, to support such upper section.

Having thus described my invention, now 65 what I claim is—

In a vapor face bath or inhaling apparatus, in combination, a receptacle for the hot liquid, an upper case A having flaps b and a shield d, an air-duct extending from the exterior to 70 the interior of said case A, said air-duct being provided with a flexible tube and suitable mouth piece, attached to its interior end, and with means for filtering the air entering through it, and the said receptacle and upper 75 case being respectively adapted to be put together, substantially as set forth.

In testimony whereof I have hereunto affixed my signature in the presence of two witnesses.

HARRIET H. HOGE.
